L. BUCKNER

TWO-PART HEEL

Filed Jan. 2, 1923

By Whitemore, Hull, Whitemore, & Bellmore,
Attorneys.

UNITED STATES PATENT OFFICE.

LEON BUCKNER, OF OAKLAND, MICHIGAN.

TWO-PART HEEL.

Application filed January 2, 1923. Serial No. 610,103.

This invention relates to two part heels and is in the nature of a further development of the construction shown in applicant's copending application, Serial Number 501,415, filed September 17, 1921.

In said copending case, in common with the present application, there is disclosed a two part heel comprising a central permanently affixed portion having substantially a U-shape and a quick detachable U-shaped outer portion normally embracing said central portion and retained in place by suitable quick releasable fastenings.

The present invention consists in an improved quick releasable fastening for normally holding the detachable element of the heel in place and further consists in the curved shape of the plate which is embedded in the removable element and holds the same in place whereby in use said plate is under a stress tending to insure a firm seat of the detachable element upon the shoe.

In the drawings:

Figure 1 is a bottom view of the improved heel with its parts assembled;

Figure 2 is a similar view showing the quick-removable element of the heel detached with a portion thereof broken away to show the reinforcing plate;

Figure 3 is a vertical sectional view on line 3—3 of Figure 1;

Figure 4 is a cross section on line 4—4 of Figure 1;

Figure 5 is a cross section on line 5—5 of Figure 2 showing the outer member of the heel detached;

Figure 6 is a bottom view of the heel portion of a shoe to which the inner part of the improved heel is shown fixed;

Figure 7 is a sectional view similar to Figure 3 but showing an alternative form of the invention;

Figure 8 is a detail view of the latch plate for the center heel part of the structure shown in Figure 7.

In these views the reference character 1 designates the permanently affixed heel portion of a shoe which ordinarily is formed of leather. The improved heel comprises substantially U-shaped inner and outer parts 2 and 3 respectively, the latter detachably embracing the former and both being prefer-

ably formed of rubber. The inner member 2 is permanently secured to the leather heel member 1 by screws 4 or other suitable permanent fastenings. The portion of said inner member close adjacent the heel member is reduced in width and also, at the back, in length, as indicated at 2^a, to form a horizontally elongated neck portion. 5 is a sheet metal plate embedded in the part 2 reinforcing the same and further forming a latch member coacting with a sheet metal plate 6 embedded in the part 3 to hold the latter part in its position of use. The plate 6 is formed with a plurality of holes 6^a through which the rubber above and below said plate is integrally connected and said plate is furthermore formed with a U-shaped central opening 6^b proportioned to embrace the neck portion 4 of the part 2. The portion of the plate 6 marginal to the opening 6^b projects inwardly beyond the rubber body of the part 3 and in this projecting portion, struck-out tongues 7 are formed, one at each side of the opening 6^b. The plate 5 is also formed with holes indicated at 8 providing for an integral connection between portions of the part 2 above and below said plate. At each side, the plate 5 projects laterally beyond the neck portion 4 just above the main body of the part 2 and these projecting marginal portions are formed respectively with slots 9 in which the tongues 7 of the plate 6 engage when the parts 2 and 3 are in assembled relation. When said relation is established the inner marginal portion of the plate 6 engages above the outer marginal portion of the plate 5 so that the latter plate and the detachable part 3 which it carries are held by the plate 5 from any downward movement relative to the part 2. Forward or lateral movement of the part 3 relative to the part 2 is prevented by the embracing relation of the part 3 with respect to the part 2. Rearward shifting of the part 3 relative to the part 2 is prevented by engagement of the tongues 7 in the slots 9. At the rear ends of said slots there are formed downwardly deflected lugs 10 which act as stops engageable by the free ends of the tongues 7 to hold the part 3 in place, this relation being best illustrated in Figure 3.

It will be understood that as the part 3 is slid forwardly into its position of use, the plate 6 rides upon the plate 5, the latter deflecting the tongues 7 upwardly. Said tongues snap into the slots 9 and engage the lugs 10 as the part 3 reaches its position of use. Removal of the outer element 3 may be effected by springing the tongues 7 upwardly out of the slots 9 as by means of a nail or some similar shaped instrument inserted through holes 11 formed in the part 2 in registration with the free ends of said tongues, as best seen in Figures 1 and 3. It will be noted that the lugs 10 are so inclined as to insure against binding of the tongues 7 on said lugs.

With reference to Figure 5, it will be seen that the plate 6 which is preferably formed of tempered steel is bowed upwardly slightly from its center line to its lateral edges. However, in sliding the part 3 into engagement with the part 2, the inner marginal portions of the plate 6 are upwardly deflected through engagement with the plate 5, as is best illustrated in Figure 4. Thus the plate 6 in use is under a stress which holds the member 3 firmly pressed against the leather heel of the shoe. Thus there is avoided any crack or gap between the detachable part 3 and the fixed leather heel element 1, which would detract from the appearance of the shoe and also admit and retain moisture.

It is a further feature of the invention that the legs of the outer part 3 are formed with slight upward projections at their free extremities, as indicated at 12, in Figure 8, this increase of thickness tending to maintain a firm contact between said ends and the engaged under face of the permanent heel member 1. For similar reasons the inner heel member has its top face raised slightly at the forward end of said member.

In the alternative form of the invention shown in Figures 7 and 8 the improved heel comprises inner and outer members 13 and 14 reinforced respectively by plates 15 and 16 just as in the first described form of the invention. The latch tongues 17 upon the plate 16 in the alternative construction project, however, forwardly instead of rearwardly and have preferably down-turned ends, as indicated at 17^a, said ends being engageable in notches 18 provided in the plate 15. As in the first described form of the invention, the outer member 14 is removable after the tongues 17 have been released from the notches 18 through insertion of a nail or the like through suitable openings 19 extended through the inner part 13. Preferably the plates reinforcing the parts 2 and 3 or 13 and 14 are copper plated as a preventative of corrosion, and to insure adhesion of the rubber to the metal.

It will be noted that the inner heel mem-

ber, as shown in Figure 7, has lesser thickness than the outer member so that the lower surface of the inner member lies above that of the outer member.

What I claim as my invention is:—

1. A heel comprising inner and outer parts of substantially a U-shape, the latter embracing the former, the inner part being substantially permanently affixed to a shoe, plates respectively embedded in said parts, the inner part having a neck portion of reduced width, and the plate carried by the outer part having a central opening for embracing said neck, and having a marginal portion engaging above an outer marginal portion of the plate carried by the inner part when the outer part is slid longitudinally into engagement with the inner part, and spring tongues upon the marginal portions of one of said plates the other plate having slots in which said tongues engage to hold the two heel parts assembled.

2. A heel comprising inner and outer U-shaped parts, the latter embracing the former, and plates carried by said parts having portions overlapping to maintain said parts assembled, the plate carried by the outer part being transversely bowed and stressed reversely to its normal curvature through engagement with the plate of the inner member to press said outer part into firm engagement with the shoe.

3. A heel comprising inner and outer substantially U-shaped parts, the latter detachably embracing the former, and plates embedded in said parts having portions projecting therefrom and overlapping in the engaged position of said parts to maintain said position, one of said parts being formed of spring metal and being transversely stressed when in engagement with the plate carried by the other part to force the outer part of the heel into firm engagement with a shoe.

4. A heel comprising a substantially permanent part and a replaceable part, and plates carried by said parts having portions overlapping to maintain said parts assembled, the plate carried by the replaceable part being normally bowed, and stressed reversely to its normal curvature through engagement with the plate of the permanent part to press said replaceable part upwardly against a portion of said permanent part under the spring stress of said bowed plate.

5. A heel comprising a substantially permanent part and a replaceable part, and metallic plates carried by said parts engageable to maintain said parts assembled, one of said plates bodily forming a spring adapted to be stressed bodily through engagement with the other plate whereby said removable part is pressed firmly against said permanent part.

6. A heel comprising a substantially per-

manent part and a replaceable part, a metallic plate carried by one of said parts, and a plate carried by the other of said parts bodily forming a spring and having edge 5 portions engageable through bodily stressing said spring with opposite margins of the first mentioned plate, whereby in the assem-

bled relation of said parts the replaceable part is firmly pressed against the permanent part. 10

In testimony whereof I affix my signature.

LEON BUCKNER.
